SAFETY SWITCH

Samuel S. Prince, Binghamton, N. Y.

Application November 25, 1932. Serial No. 644,377

2 Claims. (Cl. 200—158)

The object of this invention is to provide a switch adapted to be arranged in the battery circuit of an automobile for breaking the circuit when the automobile is not in use whereby to provide a so-called dead battery circuit which will eliminate fire hazards.

A still further object of the invention is to provide a switch of the character above mentioned, which is comparatively simple in construction, 10 consists of but relatively few parts, can be easily supported from a floor board of the automobile, and quickly and easily arranged within the battery circuit.

Other objects and advantages of the invention 15 will become apparent from a study of the following description, taken in connection with the accompanying drawing wherein:

Figure 1 is a sectional elevational view taken 20 through the improved switch, certain parts being broken away and the switch shown in an opened position.

Figure 2 is a top plan view of the switch.

With reference more in detail to the drawing, 25 it will be seen that my improved switch comprises a box like casing 3 formed of suitable insulating material, and provided at its top with a removable cover plate 4 that may be bolted or otherwise secured to the floor board of an automobile.

Arranged in the bottom of the box like casing 30 3 is a pair of opposed fixed contact blocks 5—5, each of which is provided with a terminal connector 6 extending downwardly through the bottom of the box like casing 3.

The blocks 5 taper toward their upper ends to 35 provide opposed conical faces with which contact the inclined faces of vertically movable bridge contact blocks 7 that taper longitudinally toward its lower end for movement vertically into and out of position between the contact blocks 5.

The bridge contact 7 is threaded engaged or 40 otherwise secured to the lower end of a rod 8, the upper threaded end of which extends through an opening provided in the cover plate 4. A spring 9 is convoluted about the rod 8 between the top of the bridge contact block 7 and cover plate 4 for normally urging the rod 8 downwardly of the casing.

The upper threaded end of rod 8 has threaded 45 engagement with a tubular rod 10 the lower edge of which rests on a washer 11 disposed circumjacent the rod 8 and supported on the cover plate 4.

The tubular rod 10 extends through the top of 50 a cylindrical housing 12 bolted at its lower end

as at 13 to the cover plate 4. The upper outer end of the tubular rod 10 is provided with a handle 14 and spaced downwardly from the handle 14 is equipped with a collar 15 engageable with the top of the tubular housing 12 whereby to prevent longitudinal displacement of the tubular rod 10 so that the rod 10 is constrained to rotate about a vertical axis.

In actual practice, the cover plate 4 is bolted to the floor board of an automobile, the casing 3 extending through a suitable opening provided therefor in the floor board. A wire from the battery is connected to one of the terminals 6, and a ground wire is connected to the other terminals 6 and also suitably connected to the frame or other suitable part of the automobile structure. To close the battery circuit, tubular rod 10 is rotated toward the left in Figure 1 causing rod 8 to move vertically downwardly whereby bridge contact block 7 is moved into engagement with the contact block 5 for closing the switch and completing the battery circuit. When the automobile is not in use, and it is desired to break or cause "a dead battery circuit" rod 10 is rotated in the opposite direction, causing rod 8 to move upwardly into the rod 10 thus raising the bridge contact block 7 out of engagement with the contact block 5 thus interrupting the battery circuit.

When the circuit is thus interrupted, it will be apparent that the possibility of fire, as would otherwise be caused were the battery circuit left uninterrupted, is obviated.

Even though I have herein shown and described the preferred embodiment of the invention, it is to be understood that the same is susceptible of further changes, modifications and improvements coming within the scope of the appended claims.

Having thus described my invention, what I claim as new is:

1. A circuit controlling switch comprising a casing, a pair of fixed contacts arranged in said casing, a cylindrical housing supported on one wall of said casing exteriorly thereof, a tubular rod rotatably supported in said housing, a threaded rod having threaded engagement with said tubular rod for axial movement relative thereto, and extending into said casing, a contact on said threaded rod for movement therewith into and out of engagement with said first mentioned contacts, and a spring convoluted about said threaded rod and interposed between said movable contact and said one wall of said casing.

2. An electric switch of the class described comprising a casing of insulating material and

rectangular in cross section, a pair of contacts fixed in the bottom of the casing and having opposed faces oppositely inclined, a lid secured to the top of the casing, a tubular housing secured at one end to the lid, an operating rod rotatably confined in the housing between one wall thereof and the lid against longitudinal movement relative to the housing, a shank extending through

an aperture in the lid and having threaded engagement with the tubular rod, and a wedge shaped contact member engaged with one end of the stem and having sides thereof arranged to engage the inclined sides of the fixed contacts, 80 together with a spring disposed about said shank between said lid and wedge shaped contact.
